S. C. Hofmann
BY A. L. Vencile

His ATTORNEY

UNITED STATES PATENT OFFICE.

SEBASTIAN C. HOFMANN, OF CHAMPAIGN, ILLINOIS.

ELECTRICAL RELAY.

Application filed November 21, 1924. Serial No. 751,230.

To all whom it may concern:

Be it known that I, SEBASTIAN C. HOFMANN, a citizen of the United States, residing at Champaign, in the county of Champaign and State of Illinois, have invented certain new and useful Improvements in Electrical Relays, of which the following is a specification.

My invention relates to electrical relays, 10 and particularly to alternating current induction motor relays of the vane type.

One feature of my invention is the provision, in relays of this type, of a construction which will prevent the vane from occupying an intermediate position wherein both the front and the back contacts are open when the relay is under-energized.

I will describe one form of relay embodying my invention, and will then point out 20 the novel features thereof in claims.

In the accompanying drawing, Fig. 1 is a view showing in front elevation one form of relay embodying my invention. Fig. 2 is a top plan view of the electro-magnetic elements of the relay shown in 25 Fig. 1.

Referring to the drawing, the relay comprises a vane 2 pivotally mounted at 2^a and biased by its own weight to the position in 30 which it is shown in the drawing wherein it rests against a stop 3. The vane swings between the poles of a U-shaped magnetizable core 4 provided with a winding 5 which as here shown is in two sections one being on 35 each leg of the core. The upper portion of each pole is surrounded with a copper ferrule 6 whereby when the winding 5 is supplied with alternating current the vane 2 is subjected to a shifting magnetic field 40 which swings the vane in clockwise direction against the force of gravity until it engages a front stop 7.

The vane 2 controls a back contact 8 and a front contact 9 in the usual manner, that 45 is, through the medium of a rocker member 11, an arm 12 attached to member 11, and a link 13 connecting the arm 12 with a crank 14 on the shaft 2^a. When the relay is de-energized so that the vane is in its biased or lower position, the back contact 8 is closed and the front contact 9 is open; whereas, 50 when the relay is energized so that the vane is shifted to its upper position against the front stop 7, the back contact 8 is open and the front contact 9 is closed. The contact arrangement is such that when the relay

becomes de-energized the front contact 9 opens before the back contact 8 closes, and conversely, when the relay becomes energized the back contact 8 opens before the front contact 9 closes.

Relays of the type shown in the drawing are so well known in the art of railway signaling that a more detailed description of the structure is unnecessary. I have 65 found that when the current in winding 5 drops to a value considerably below normal, that is, when the relay is under-energized, the vane 2 may drop away from the front stop 7 and assume a position of rest wherein both the front contact 9 and the back contact 8 are open. This is undesirable, and I have found that it may be prevented by cutting a slot 10 in the vane 2. The size of this slot will depend on the size and 75 characteristics of the relay; for a relay of the size shown in the drawing the slot is preferably about $\frac{1}{2}$ inch by $1\frac{1}{8}$ inches in size, the long dimension being radial with respect to the pivotal axis 2^a of the vane, and the slot is preferably so located that it substantially registers with the ferrules 6 when the vane is in its lowest position. This slot causes the relay to have positive pick-up and release voltages, so that there is no 80 voltage at which the vane will remain in an intermediate position wherein the front and back contacts are both open.

Although I have herein shown and described only one form of relay embodying 90 my invention, it is understood that various changes and modifications may be made therein within the scope of the appended claims without departing from the spirit and scope of my invention.

Having thus described my invention, what I claim is:

1. An induction motor relay comprising a vane, and front and back contacts controlled by said vane, said vane being provided with a single slot whereby either said front or said back contact will be closed when the relay is under-energized.

2. A relay comprising a winding which is at times supplied with alternating current, a vane inductively operated by alternating current in said winding, a front contact and a back contact controlled by said vane and closed respectively when said winding is energized and de-energized, the front contact being arranged to open before the back contact closes when the winding

- becomes de-energized and vice-versa, said vane being provided with a slot to prevent the vane occupying a position wherein both contacts are open when said winding is under-energized.
3. An induction motor relay comprising a vane, a front and a back contact controlled by said vane and so arranged that the front contact opens before the back contact closes when the relay becomes de-energized and vice-versa, said vane being provided with a slot to prevent the vane occupying a position wherein both contacts are open when the relay is under-energized.
- 10 4. An induction motor relay comprising a vane, a front and a back contact controlled by said vane and so arranged that the front contact opens before the back contact closes when the relay becomes de-energized and vice-versa, said vane being provided with a slot approximately one-half inch by one and one-eighth inches in size to prevent the vane occupying a position wherein both contacts are open when the relay is under-energized.
- 15 5. An induction motor relay comprising a vane, and front and back contacts controlled by said vane, said vane being provided with a single slot approximately one-half inch by one and one-eighth inches in size to prevent the vane from occupying a position wherein both said contacts are open when the relay is under-energized.
- 20 6. A relay comprising a core having confronting poles, a ferrule surrounding a portion of each pole, a winding for said core, a vane mounted to swing between said poles, and front and back contacts controlled by said vane and so arranged that the front contact opens before the back contact closes when the relay becomes de-energized and vice-versa, said vane being provided with a slot approximately one-half inch by one and one-eighth inches in size, located to substantially register with said ferrules when the relay is de-energized.

In testimony whereof I affix my signature.

SEBASTIAN C. HOFMANN.
